Patented May 15, 1928.

UNITED STATES PATENT OFFICE.

WILLIAM O. THOMPSON, OF PITTSBURGH, PENNSYLVANIA, ASSIGNOR TO STANDARD SANITARY MFG. CO., A CORPORATION OF PENNSYLVANIA.

FLUSH-PIPE HOUSING.

Application filed August 4, 1927. Serial No. 210,679.

This invention relates to sanitary fixtures and particularly to flush pipe housings.

I have found in practice the desirability of a flush pipe housing that may be removed from the flush pipe without disconnecting the flush pipe connections from the other parts of the fixture. Housings that have been heretofore used for flush pipes are undesirable due to the necessity of having to disconnect the flush pipe in order to remove the housing and one object of this invention is to provide a flush pipe housing that shall be detachable from the sanitary fixture without disconnecting the flush pipe connection.

Another object of this invention is to provide a flush pipe housing having a detachable means for securing the housing in fixed relation to the flush pipe without interfering with the flush pipe connections.

Another object of this invention is to provide a sanitary fixture comprising a flush pipe having off-set connections and a housing therefor that may be secured to the pipe or detached therefrom independent of any connections of the fixture.

A further object of this invention is to provide a flush pipe having a detachable housing of the above characteristics that shall be simple in structure, practical in operation and inexpensive to manufacture.

These and other objects that may be made apparent through the description of this invention are attained by means of the apparatus hereinafter described and illustrated in the accompanying drawings wherein,

Figure 1 is a partial side elevational view partly in cross section of a sanitary fixture embodying the invention.

Fig. 2 is a back elevational view of a flush pipe housing embodying a part of the invention.

Fig. 3 is a top plan view of a detail forming a part of the invention.

Fig. 4 is a side view in elevation of Fig. 3 and,

Fig. 5 is a sectional view taken along the line V—V of Fig. 4.

This invention comprises in general a flush pipe 11 for connecting a tank 12 and a bowl 13 of the conventional type, a detachable housing 14 for the flush pipe 11 and

means 15 for securing the housing to the flush pipe.

Tank 12 and bowl 13 are connected to the flush pipe by any suitable connections such as 16 and 17 and the flush pipe 11 may be adapted for straight connections or for offset connections as the installation may require.

The housing 14 may be of any desired design and may be built for utilization with any desired form of flush pipe either straight or as illustrated in the drawings.

Referring particularly to Figs. 1 and 2 the housing 14 is provided with a vertical opening 18 in its rear wall for receiving the flush pipe 11 and an inwardly projecting flange 19 disposed on the lower portion of its inner face, the said flange being integral with the housing and in a plane substantially parallel to the plane of the base of the housing. The end portions of the flange 19 adjacent the opening 18 in the rear wall are provided with openings 21 and 22 for cooperating with a clamping device 23 for securing the housing in fixed relation to the pipe as will hereinafter be described.

The means 15 referred to above comprises the clamping means 23 and the flange portion 19. The flange portion 19 is adapted to receive the pipe 11 and the distance between its inner opposite faces is slightly greater than the external diameter of the pipe 11. The means 23 is adapted to engage the openings 21 and 22 in the flange 19 for clamping the housing 14 in a rigid fixed relation to the pipe 11.

Referring particularly to the Figs. 3, 4 and 5 the clamping means 23 comprises a main body portion 24 of arcuate shape, the ends of which terminate in projections 25 and 26 at substantially right angles to the plane of the main body portion 24. The main body portion 24 is provided with a threaded stud 27 disposed on one of its sides at substantially mid position. At this point the main body portion is curved outwardly to align the stud 27 with the projections 25 and 26. The stud 27 is disposed in a plane substantially at right angles to the planes of the projections 25 and 26. The stud 27 and body portion 24 are provided with an adjustable locking member 28 having an opening therein for receiving the stud and a slot 29 in the bottom portion

thereof for receiving and cooperating with a curved portion of the main body portion 24. A wing nut 31 is threaded to the stud 27 for actuating the adjustable locking member 28.

In practicing my invention I position the housing 14 around the pipe 11 through the vertical opening 18 which permits the flange portion 19 to receive the pipe, at 10 which time the projections 25 and 26 of the clamping means 23 are brought into engagement with openings 21 and 22 of the flange 19. By tightening the wing nut 31 the locking member 28 is pressed against the corresponding face of the pipe 11 pressing the pipe 11 against the inner faces of the flange 19 thereby securing the housing 14 in a rigid fixed relation with the pipe.

When it is desired to remove the housing 14 from the pipe 11, it is only necessary to 20 loosen the wing nut 27 and remove the clamping means 23 from engagement with the flange 19 at which time the housing 14 may be removed from the pipe 11 without 25 interfering with any of the connections of the fixture.

From the above it can be seen that I have provided a sanitary fixture comprising a tank and a bowl to be connected by a flush 30 pipe and a detachable housing for the flush pipe that may be positioned and rigidly fastened about the flush pipe independent of any connection of the fixture.

While I have illustrated and described but 35 one embodiment of this invention it will be apparent to those skilled in the art that flush pipe housings may be built for either straight or off-set connections as well as other changes, modifications, substitutions, 40 additions, and omissions may be made in the structure described without departing from the spirit and scope of the appended claims.

What I claim as new and desire to secure by Letters Patent is:

1. A sanitary fixture comprising a flush 45 pipe, a detachable housing therefor and means for securing the housing to the pipe, the said means comprising an adjustable clamp for engaging the side walls of the housing.

2. A sanitary fixture comprising a flush pipe, a detachable housing therefor, the said housing having an integral inwardly extending flange portion for engaging the pipe and an adjustable means for engaging the opposite sides of the flange portion and pressing against the pipe for securing the housing in rigid connection to the pipe.

3. A sanitary fixture comprising a flush pipe, a housing therefor having a vertical 60 opening therein, an inwardly extending flange portion projecting from the inner wall of the housing for engaging the pipe and means for engaging the outer ends of the projections and cooperating with the pipe 65 for maintaining the housing in fixed relation with the pipe.

4. A sanitary fixture comprising a flush pipe, a housing therefor having a vertical opening therein, an inwardly extending 70 flange portion projecting from the inner wall of the housing for engaging the pipe and means for engaging the outer ends of the projections and cooperating with the pipe 75 for maintaining the housing in fixed relation with the pipe, the said means comprising an arcuate shaped member having a threaded stud disposed at substantially mid position and provided with a projection at each of its ends disposed at substantially 80 right angles to the main body portion, a locking member and a wing nut for the threaded stud for actuating the locking member.

In testimony whereof, I have hereunto 85 subscribed my name this 22nd day of July, 1927.

WILLIAM O. THOMPSON.
